2,043,793

ELECTRIC LIGHTING APPARATUS

Joseph O. Cadienx, Meriden, Conn., assignor to
Connecticut Telephone & Electric Corporation,
Meriden, Conn., a corporation of Delaware

Application November 15, 1930, Serial No. 495,886

5 Claims. (Cl. 177—329)

My invention relates particularly to luminescent gas tube lamps intended for traffic signaling systems.

One object is to provide simple, convenient and durable means for mounting signal lamps of this character. Another object is to provide a combination transformer and lamp construction suitable for traffic signaling. Another object is to provide means for supporting and adjusting a luminescent gas tube. Another object is to provide means for supporting a number of lamps in a single casing.

Fig. 1 is a front view of a construction embodying my invention.

15 Fig. 2 is a side view of the same.

Fig. 3 is a front view of a double unit, one being arranged beneath the other.

Fig. 4 is a plan view of another duplex construction the two units being arranged at right angles to each other.

Fig. 5 is a horizontal section and plan of a lamp embodying my invention and showing two tubes with their sockets and transformers in a single casing on the line 5—5 of Fig. 1.

25 Fig. 6 is a vertical section and front view of the construction shown in Fig. 5 on the line 6—6 of Fig. 5.

The housing 1 could be of any suitable material and construction supported either from a hanger 8 or on a pedestal at base 8'.

Within the casing 1 mount one or more tubes such as 9 containing a suitable luminescent gas of the desired light emitting color. Each tube is preferably of a spiral form having its terminals

35 mounted in a base 10 which is adapted to be supported by a socket 11. The connection is effected through prongs 12 insertable in clips 13. The socket is adapted to be adjusted horizontally in the casing by one or more screws such as 14 and

40 15. Each tube may be supported at one or more places, for instance, by brackets such as 16 to supplement the support received from the base of the lamp.

In some lamps of this character it is desirable 45 to supply current from ordinary lighting mains having a potential of 110 or 220 volts and in such cases it may be necessary or desirable to use a transformer 17 to step up the potential to that required for the particular tube employed. The

50 casing of the transformer may conveniently support the socket 11 or its lamp tube. The transformer may be held in place by a flange 18 within the casing. In order to use a standard and symmetrically disposed type of casing 1 may make the 55 casing large enough on both sides to accommo-

date two units and may mount one unit in one side of the casing and the other unit in the other side as shown in Fig. 5. In such case a filler plug 17' may be used to fill in the vacant space alongside of the transformer 17. The end of the casing may be closed by a plate 19.

A glass or lens 20 may be employed on one or both sides, or a screen 21 may be employed in order to protect the lamp tubes within the casing. Shields 22 may be employed as is common 10 in signal lighting.

It will be understood that the primary conductors will be led in to the casing in any suitable manner as for instance through the top or supporting member 8 as shown in Fig. 6.

The lamp thus far described is obviously capable of showing signals in two directions only although it may be rotated to show signals in other directions. When it is desired to signal in two directions at right angles to each other without rotating the lamp, two lamps may be provided as shown in Fig. 3. In this instance the upper unit corresponds with the construction previously described and the lower unit is similarly constructed but arranged with its light directing members 20 at right angles to the upper unit.

In the construction shown in Fig. 4 there are two units supported on a pedestal or post 25 at right angles to each other. These may be both arranged in a common plane but faced in directions at right angles to each other so as to control a four-way traffic.

Lamps of this character have the distinct advantage of long life and small current consumption. Furthermore it is possible to produce a 35 wide variety of colors by using proper gases and at the same time employ transparent glass tubing, which is a much more efficient method of lighting than the use of differently colored glasses.

I wish it understood that the construction may be varied to conform with local highway intersection requirements so that a single lighting unit may be used at a dead end intersection and that additional units may be added where 45 the number of intersecting highways makes this necessary or desirable. While the forms shown in Figs. 3 and 4 are at right angles, the angular displacement of the units may be adjusted to suit the direction of approach over roads that 50 intersect at other angles.

I claim:

1. Traffic signal apparatus comprising a casing having a central compartment with extension compartments on each of the two sides and 55

windows centrally disposed in two other sides, a transformer and tube socket mounted in each of said extension compartments, said sockets being offset with respect to each other, and luminescent gas tubes adapted to be mounted in said sockets and to overlap one another in line with said windows.

2. Traffic signal apparatus comprising a casing having a central tube compartment with lateral extensions and intervening windows, said extensions having detachable end plates, a transformer and connected socket mounted in each extension, a luminescent gas tube mounted in each of said sockets, the latter being offset to permit the tubes supported thereby to overlap each other.

3. In traffic signal apparatus a housing having aligned openings in opposite sides thereof and two diametrically disposed extensions, transparent covers for said openings, a plurality of compact spirally disposed luminescent gas tubes adapted to emit different colored lights when energized, means for supporting said tubes in said casing in laterally displaced planes parallel to said covers, the centers of the spirals being substantially in line with the center points of said covers, and means including transformers in each of two diametrically disposed extensions of said housing for energizing each of said tubes independently of the others, each of said tubes being effective to transmit rays through each of said covers.

4. Traffic signal apparatus comprising a casing having a central compartment, diametrically disposed extension compartments on two sides of said casing, transparent windows in two other sides, a transformer and a tube socket mounted in each of said extension compartments, said sockets being laterally spaced in a plane perpendicular to said windows, spirally wound luminescent gas tubes supported in said sockets in line with said windows, one of said tubes overlapping the other.

5. Traffic signal apparatus comprising a casing having a central compartment, diametrically disposed extension compartments on two sides of said casing, transparent windows in two other sides of the casing, a transformer in each of said extension compartments and movable therein, a tube socket operatively connected to each of said transformers, pairs of members movably supported in opposed walls of said casing and having threaded engagement therewith, the members of each pair being in axial alignment with one another with the inner ends thereof engaging opposite sides of one of said sockets whereby the latter may be adjusted transversely of said housing, luminescent gas tubes each of large light emitting area compared to said windows supported in said sockets in overlapping position between said windows whereby each of said tubes transmits light through both of said windows.

JOSEPH O. CADIEUX.
